UNITED STATES PATENT OFFICE.

LEVI H. KELLAM, OF SANDWICH, ILLINOIS.

MANURE-SPREADER.

No. 820,781.

Specification of Letters Patent.

Patented May 15, 1906.

Application filed April 13, 1905. Serial No. 254,835.

To all whom it may concern:

Be it known that I, LEVI H. KELLAM, a citizen of the United States of America, and a resident of Sandwich, in the county of DeKalb and State of Illinois, have invented certain new and useful Improvements in Manure-Spreaders, of which the following is a specification.

This invention relates to that class of manure-spreaders in which the manure is carried rearward by a traveling apron and evenly and gradually distributed on the ground by a rotating beater-cylinder arranged at the rear of the machine; and the present invention has for its object to provide a simple, durable, and efficient structural arrangement and combination of parts affording a perfect control of the various operating mechanisms of the machine by the operator from the usual driver's seat and with which the various operating mechanisms are controlled, so that any one mechanism while in active operation locks an opposing operating mechanism in a dormant condition until such first-mentioned mechanism completes its movement and becomes automatically dormant, or rendered dormant in a manual manner by the operator, all as will hereinafter more fully appear and be more particularly pointed out in the claims.

In the accompanying drawings, Figure 1 is a side elevation of a manure-spreader illustrating the general arrangement of the present invention. Fig. 2 is a skeleton perspective view of the various operating mechanisms of the manure-spreader. Fig. 3 is a detail plan view illustrating the mechanisms for imparting motion to the traveling apron and the beater-cylinder. Fig. 4 is a fragmentary longitudinal sectional elevation of the front portion of the main body, illustrating a portion of the mechanism for stopping the forward movement of the traveling apron. Fig. 5 is a detail transverse section illustrating the central support for the traveling apron. Fig. 6 is a detail longitudinal section of the rear portion of the manure-spreader. Fig. 7 is a detail plan view of the beater-cylinder. Fig. 8 is a detail rear elevation of the pressure-comb.

Similar numerals of reference indicate like parts in the several views.

As represented in the drawings, the present manure-spreader in its general arrangement comprises the usual box-shaped body 1, having a skeleton frame at its under side and mounted in any usual and suitable man-

ner upon the front and rear ground-wheels 2 and 3, with its actual bottom formed by a longitudinally-moving apron 4, adapted to carry the load of manure in a gradual manner 60 toward a rotary spreader or beater-cylinder 5, mounted at the rear of the main body in a transverse direction, as usual in the present type of manure-spreaders.

The traveling apron aforesaid comprises a 65 series of slats extending the interior width of the main body and flexibly connected together by chain-links 6 at their mid-length and respective ends. Said chain-links just referred to have bearing in the usual manner 70 upon rollers secured to the under frame of the main body to support the apron in proper position as the bottom of said body, and the middle links constitute the driving means for the apron and to this end are provided 75 with a series of additional links 7 to form an endless chain which passes around operating sprocket-wheels 8 and 9, journaled, respectively, at the front and rear ends of the main body aforesaid.

10 is the usual transverse shaft arranged underneath and at the mid-length of the main body and provided with supporting-rollers 11, upon which the tail portion of the manure-carrying apron 4 rides and is supported against 80 sagging during the last part of its movement of discharge and the corresponding first part of its movement of return. In the present improvement the initial riding of the apron into position upon the rollers 11 is insured by 85 means of a link 12, arranged at the point of connection of the aforesaid additional chain-links 7 to the tail end of the apron and provided with an inclined rib 13 on its under side adapted to ride upon the central one of 90 the rollers 11 and lift the tail of said apron above said rollers a distance sufficient to prevent a catching of the tail of the apron against the rollers and avoid the consequent breakage of parts which might ensue.

The mechanism for imparting a rearward travel to the manure-carrying apron and for varying the speed of the apron in such rearward travel consists of the following means:

14 is a gear-wheel revolving in unison with 105 a ground-wheel 3 of the machine and imparting motion in turn to a secondary gear-wheel 15, journaled upon a supporting-arbor 16, secured to the main body 1 of the machine.

17 represents a series of annular gears arranged concentrically on the inner face of the gear-wheel 15 aforesaid.

18 is a pinion slidably mounted upon a shaft hereinafter described and adapted to be moved into engagement with either of the series of annular gears 17 to receive therefrom different speeds of rotation in accordance with the speed at which it is desired to have the apron travel in its discharge movement.

19 is a sleeve connected to the hub of the pinion 18 in a manner which permits of an independent rotation of said pinion, and 20 is a connecting-link extending from said sleeve to a hand-lever 21 at the front of the machine and by which the operator is enabled to effect a sliding adjustment of said pinion in a convenient and effective manner in the operation of changing the speed of the rearward and discharge travel of the apron.

22 is an intermediate longitudinal shaft, at one end of which is the longitudinally-adjustable pinion 18 aforesaid and at the other end a worm 23, adapted for operative engagement with a worm-wheel 24 at one end of the shaft of the rear apron sprocket-wheel 9.

25 is a bearing-sleeve mounted in a slideable manner upon the supporting-arbor 16 aforesaid and forming a bearing for the forward end of the longitudinal pinion-shaft 22 aforesaid and adapted in one of its adjustments to maintain the pinion 18 in mesh with one or the other of the annular gears 17 and in its other adjustment to move such pinion clear of the path of such annular gears, so that the longitudinal adjustment of said pinion upon the pinion-shaft, as above described, can be effected to bring the pinion into proper relative position for engagement with a particular annular gear 17, affording the speed of revolution required. Said bearing-sleeve is provided with a spiral rib 26 at one side of its periphery and with a complementary spiral recess 27 at one end, as shown in Fig. 3, for engagement with the operating-arm now to be described.

28 is an oscillating operating-arm journaled on the arbor 16 aforesaid and provided with an inclined projection 29, adapted to have bearing engagement against the inclined face of the spiral recess 27 of the sleeve 25, so that when said arm is oscillated in one direction the said bearing-sleeve will be forced outward to engage the pinion 18 with one of the annular gears 17, before described. Such arm is also provided with a hook-shaped toe 30, adapted for engagement with the outer inclined surface of the spiral web 26 on the sleeve 25 aforesaid, so that when said arm is oscillated in the other direction the bearing-sleeve will be drawn inward to move the pinion 18 out of its engagement with the annular gear 17 aforesaid.

31 is an operating hand-lever at the front of the machine; and 32 is a connecting-link extending from said lever to the free end of the oscillating arm 28 to afford means for the

convenient operation of the parts by the operator at the front of the machine.

33 is a movable bearing carrying the rear end of the shaft 22, and 34 is a cam member pivotally attached to one side of the main body and provided with a cam-groove 35, engaging said bearing, as usual in the present type of manure-spreaders. The arrangement of parts is such that an oscillation of said cam member in one direction will lift the worm 23 out of engagement with the worm-wheel 24, while a reverse oscillation will place said worm and worm-wheel in operative engagement.

36 is a connecting-link attached to the cam member aforesaid and extended to the forward end of the machine for attachment to an automatic actuating means hereinafter more fully described.

The mechanism for imparting a return or forward travel to the manure-carrying apron consists of the following means:

37 is a pinion meshing with and receiving motion from the gear-wheel 15, before described. Such pinion is revolvably mounted on a supporting-arbor 38 on the side of the main body and is provided with a clutch member 39 on one of its faces.

40 is a chain-wheel arranged on the arbor 38 in adjacent relation to the pinion 37 and provided with a clutch member 41 on its face, adapted for engagement with the clutch member 39, before described. Such chain-wheel is adapted to have endwise movement on said arbor in order that it may be moved into and out of operative engagement with the pinion 37 aforesaid.

42 is an endless chain connecting the chain-wheel 40 with a companion chain-wheel 43 on one end of the shaft of the forward apron sprocket-wheel 8.

44 is a bell-crank lever pivoted to the main body with one arm in operative engagement with the chain-wheel 40 and with the other arm connected to the rear end of a link 45, which in turn is connected to one end of a secondary lever 46, pivoted at the forward end of the main body, as illustrated in Fig. 2.

47 is a hand-lever pivoted at its lower end on a stud 47^a to the front end of the main body and operatively connected by a link 48 with the secondary lever 46 aforesaid.

49 is a spring connected to the lever 47 and adapted to draw said lever and the intermediate connections between said lever and the chain-wheel 40 in a direction which will release said chain-wheel from its engagement with the pinion 37 aforesaid, so that the normal tendency of said spring is to maintain the mechanism for imparting a return movement to the manure-carrying apron in a dormant condition.

50 is a catch-piece secured to the main body and behind which the lever 47 is adapted to engage and be held when said lever is

manually moved against the stress of the spring 49 to clutch the chain-wheel 40 to the pinion 37 and effect an active movement of the aforesaid mechanism by which the return 5 movement is imparted to the manure-carrying apron.

51 is a pendent arm pivoted at its upper end to the main body and provided with an intermediate angular bend or projection 52, 10 arranged in line with the lever 47 aforesaid and adapted in a forward swing to push said lever out of engagement with the catch-piece 50. The lower end of said arm is arranged in the path of the forward end of the manure-carrying apron in order that as the apron reaches the end of its return or forward movement the said arm will be moved forward to release the lever 47 from the catch 50 to allow the spring 49 to automatically release the 20 chain-wheel 40 from engagement with the pinion 37 and prevent further active movement of the mechanism by which the return travel of the apron is attained and as heretofore more fully set forth.

25 53 is a ratchet-wheel secured to the shaft of the forward sprocket-wheel of the apron, and 54 is a pivoted pawl engaging said ratchet wheel to prevent a rearward movement of the apron except when the said pawl is positively held out of engagement with said ratchet-wheel by mechanism hereinafter described.

The mechanism for imparting rotary motion to the beater-cylinder in a readily-controllable manner consists of the following 35 means:

55 is a gear-wheel revolving in unison with a rear ground-wheel 3 of the machine and imparting rotation in turn to a pinion 56, mounted on a supporting-arbor 57 on the main body in a manner to permit of a limited endwise adjustment of said pinion for purpose hereinafter set forth.

58 is a chain-wheel arranged upon the arbor 57 in adjacent relation to the pinion 56 and provided with a clutch member 59, adapted for engagement with a complementary clutch member 60 on the side of said pinion, as shown in Fig. 3.

50 61 is an endless chain connecting the chain-wheel 58 with a similar chain-wheel 62 on one end of the shaft of the beater-cylinder.

63 is a lever pivoted to the main body with one arm engaging the hub of the pinion 56 55 aforesaid and with the other arm in operative engagement between a pair of spirally-arranged ribs of an operating member now to be described.

64 is an operating-arm journaled on a supporting-arbor of the main body with its hub portion provided with a pair of spirally-arranged ribs 65, between which one arm of the lever 63 has operative engagement, as above set forth.

65 66 is a forwardly-extending link which con-

nects the free end of the arm 64 with an actuating crank-arm which constitutes a member of the hereinafter-described mechanism, by which the operations of the different mechanisms of the machine are regulated and controlled. 70

67 is a pressure-comb consisting of the usual spring teeth or fingers projecting from a carrying-shaft or back bar which is supported transversely of the main body in 75 brackets or uprights on the sides of said body and in adjacent relation to the beater-cylinder 5 of the machine. In the manure-spreading operation of the machine the comb teeth or fingers aforesaid have a rearwardly-inclined position to form in connection with the crown of the beater-cylinder a narrow discharge-throat for the manure to insure an effective separation of such manure in its passage and previous to its discharge upon the 85 field. The other position of said comb teeth or fingers is a vertically depending one in front of the beater-cylinder to form a shield for the same in the operation of loading the machine with manure. Such two positions of the 90 comb teeth or fingers are attained by an arm 68 on the comb-shaft, a connecting-link 69, and an operating-lever 70 at the front end of the main body, and having a latch or ratchet-lock 70^a, as usual in the present type of manure-spreaders. 95

The mechanism for effecting an interlocking control of the various mechanisms hereinafter described and so that one mechanism is held dormant while an opposing mechanism is in operation consists of the following means: 100

71 is a transverse rock-shaft journaled in front of the main body and provided with a hand-lever 72, by means of which a rocking 105 movement in either direction can be imparted to the rock-shaft by the operator.

73 is a spring operatively connected to the rock-shaft 71, with a constant tendency to impart a turning movement to said rock-shaft and lever in a forward and downward direction. 110

74 is a spring-latch lever pivoted to the main body and adapted for holding engagement with the lever 72 against the stress of 115 the spring 73 when said lever and its rock-shaft are moved by hand in an upward and backward direction, as illustrated in Fig. 2.

75 is a crank-arm at one end of the rock-shaft 71 in operative engagement with the 120 forward end of the link 66 of the heretofore-described mechanism for imparting rotary motion to the beater-cylinder.

76 is a crank-arm at the other end of said rock-shaft in operative engagement with the 125 forward end of the link 36 of the heretofore-described mechanism for imparting a discharge or rearward travel to the manure-carrying apron. The said crank-arms 75 and 76 are so positioned with relation to each other 130

that with a turning movement of the rock-shaft in one direction both of the mechanisms just referred to will be brought into active operation, and with a turning movement 5 of the rock-shaft in the other direction both of said operating mechanisms will be brought into a dormant or inactive condition.

77 is a link connecting the crank-arm 76 with the pivoted pawl 54 and adapted to lift 10 said pawl out of engagement with the ratchet-wheel 53 before the heretofore-described mechanism for imparting a discharge or rearward movement of the manure-carrying apron is brought into active operation by a movement of the aforesaid rock-shaft.

78 is an arm pivoted to the main body and connected by a link 79 with a crank-arm 80 on the aforesaid rock-shaft. Such arm 78 is so arranged with relation to the intermediate 20 lever 46 of the heretofore-described mechanism for imparting a forward movement to the manure-carrying apron that with the rock-shaft 71 turned into a position to cause a rearward movement of said apron the said 25 arm 78 will be lifted up into the path of the intermediate lever 46 to prevent a movement of said lever, and thereby lock the mechanism for imparting a forward movement to the apron in a dormant or inactive 30 condition. In like manner and with the rock-arm 71 turned into a position which imposes a dormant condition on the mechanism 35 for effecting a rearward movement of the apron and with the mechanism for imparting a forward movement to said apron in active 40 operation the lever 46 will lay above and in the path of said arm 78 to lock the same against upward movement while such last-mentioned conditions prevail, and accordingly 45 a dormant condition of the mechanism for imparting a rearward movement to the apron will be insured until the forward movement of the apron has taken place fully and such prevailing conditions changed by the 50 impingement to the arm 51 52 against the lever 47, as heretofore set forth.

81 is a rock-shaft arranged in a transverse direction near the front of the main body and provided with a depending arm 82, arranged 55 in the path of the rear end or tail portion of the apron and adapted to be operated thereby as said apron reaches the end of its rearward or discharge travel.

83 is a rock-arm on the shaft 81, having operative 60 connection by a link 84 with the free arm of the spring-latch lever 72 of the heretofore-described mechanism for effecting an interlocking control of the various mechanisms of the manure-spreader.

85 is a projecting pin or stud carried by the link 66 of the beater-operating mechanism and located in front of the operating-lever 70 of the pressure-comb aforesaid, and the arrangement is such that the lever 70 must be 65 moved rearwardly to place said comb in

proper operative relation to the rotary beater before the link 66 can have rearward movement to bring said beater into active operation.

The rotary beater 5 comprises in detail a 70 pair of end spiders 86 and a central spider 87, to the circular outer rims of which are secured the circular series of rails or bars 88, which carry the teeth or picks 89 of the beater. In the present improvement said rails have an 75 angular form in a direction lengthwise of the beater-cylinder, as shown in Fig. 7 of the drawings, and preferably consists of half-rails arranged end to end at the central spider 87 and extending outwardly in an oblique 80 manner to the respective end spiders 86 to constitute rails of the flattened V shape shown.

The teeth or picks 89 of each rail are staggered with relation to the teeth or picks of 85 the next adjacent rails, so as to present a quincuncial arrangement of teeth, which feature in connection with their spiral or diagonal arrangement from the central to the portion of the beater as afforded by the above-described rails, provides a simple and effective beater construction in which the stress in actual operation is uniform and continuous, the liability to clogging and crowding greatly reduced, and the manure spread broadcast 95 over an area greater than the track of the machine.

In the present improvement the pressure-comb heretofore referred to consists of a plurality of independent sections 90, preferably 100 two in number and attached by hanger-straps 91 to a common supporting-shaft 92, carried by the brackets 93 of the main body, to which shaft the operating-arm 68, before 105 described, is attached.

94 represents arms fixed to the shaft 92 by means of attaching-hubs and fastening-screws or other usual means.

95 represents yielding connections arranged between the fixed arms 94 and the back of the comb-sections, each connection comprising a projecting bolt 96 on an arm 94, a spring 97, surrounding said bolt, and an adjustable nut 98 for regulating the tension of said spring. With the described construction any one comb-section can yield under a local stress without requiring a movement of the entire comb, and in consequence the strain and drag upon the beater is correspondingly reduced and a more even and uniform manure distribution obtained.

The operation of the present manure-spreader is as follows: With the manure-carrying apron at the end of the forward travel and its dormant condition maintained by a 125 forward and downward position of the lever 72, which insures a disengaged condition of the worm 23 and worm-wheel 24 and an engaged condition of the ratchet-wheel 53 and pawl 54 to prevent an accidental rearward 130

movement of the apron, the manure is loaded into the main body upon said apron and the machine drawn to the place of distribution. The lever 72 is thus manually brought into its raised and backward position to be engaged and held by the spring-latch 74. Such movement of said lever causes a disengaged condition of the aforesaid ratchet-wheel 53 and pawl 54 to permit a rearward travel of the said apron, an engaged condition of the worm 23 and worm-wheel 24 to effect such rearward motion of said apron, and, through the instrumentality of the arm 75, link 66, operating-arm 64, and lever 63, a movement of the clutch members 59 and 60 into engagement to impart a rotary motion to the beater-cylinder, after which a distribution of the manure over the field takes place in an even and continuous manner. Before the aforesaid movement of the lever 72 and the resulting movements of the other parts above described can be attained the arrangement of the lever 70 in the path of the rearward movement of the lateral pin 85 on the link 66 requires that the said lever 70 shall be moved out of the way, and in consequence the adjustment of the pressure-comb from a loading to a distributing position is positively insured before the operation of distributing the manure can commence. With the lever 72 in the position above described the arm 78 is held up in the path of the intermediate lever 46 of the mechanism for imparting a forward travel to the manure-carrying apron by arm 80 and link 79 to lock said mechanism in a dormant condition while the rearward or discharge travel of said apron is taking place. With a gradual rearward travel of the apron the rear or tail end of said apron moves forward beneath the main body of the machine until it contacts and moves the depending arm 82, which in turn rocks the shaft 81 and arm 83 to release the spring-latch lever 74 from its holding engagement with the lever 72. Said lever 72 then moves forward and downward in an automatic manner under the influence of the spring 73. With such movement of the lever 72 a rocking motion is imparted to the rock-shaft 71, and in unison therewith the rock arm 75, through the intermediate mechanism before described, causes the clutch members 59 and 60 to separate, with a consequent stoppage of the positive rotation of the beater-cylinder. At the same time the rock-arm 76, through the link 77, lowers the pawl 54 into engagement with the ratchet-wheel 53 to prevent accidental retrograde movement of the manure-carrying apron, and said rock-arm 76, through the intermediate mechanism heretofore described, causes the worm and worm-wheel to separate with a stoppage of the rearward or discharge travel of the apron. Concurrently with said operations above described the arm 80 and link 79, moving in unison with the lever 72, push the arm 78 down out of the path of the intermediate lever 46, before referred to. The operator now draws the lever 47 in an opposite direction to the stress of the spring 49 and causes an engagement of said lever with the catch-piece 50. In such operation the lever, through the link 48, intermediate lever 46, link 45, and bell-crank 44, moves the clutch members 39 and 41 into engagement to impart a return or forward travel to the apron through the chain 42 and chain-wheels 40 and 43 and forward apron sprocket-wheel 8. During such forward travel of the apron the intermediate lever 46 lies in the path above the free end of the arm 78 to lock the same in its downward position and insures a dormant condition of the mechanism for attaining a rearward movement of the apron while the above-described forward travel of said apron is taking place. As the forward end of the apron reaches the limit of its forward travel it impinges against and moves the pendulum arm 51, which in turn effects a disengagement of the lever 47 from the catch-piece 50 and enables the spring 49 to draw said lever transversely away from said catch-piece. Such movement of the lever 47 causes a separation of the clutch members 39 and 41 through the intermediate mechanism above described, and a stoppage of the further forward movement of the apron, leaving the parts in a position for a fresh cycle of the operations just described. In effecting a change in the speed of the rearward or discharge travel of the manure-carrying apron the hand-lever 31 is moved forward and through the link 32 and operating-arm 28 effects a movement of the bearing-sleeve 25, and with it the pinion 18, away from the annular gears 17, so that said pinion will be entirely clear of said annular gears. The lever 21 is manipulated by hand to draw the pinion 18 into alignment with the particular annular gears 17 with which it is desired to have engagement, after which the lever 31 is operated in a reverse direction to that above described to move said pinion into operative engagement with the particular annular gear. 115

Having thus fully described my said invention, what I claim as new, and desire to secure by Letters Patent, is—

1. In a manure-spreader, the combination of a main body, ground-wheels carrying said body, a traveling apron forming the bottom of said body, an intermediate mechanism between a ground-wheel and the apron for imparting a rearward movement to the apron, a detachable connection forming a part of such mechanism, means for manually actuating said detachable connection, an intermediate mechanism between a ground-wheel and the apron for imparting a forward movement to the apron, a clutch forming a part of 120
2. The combination of a main body, ground-wheels carrying said body, a traveling apron forming the bottom of said body, an intermediate mechanism between a ground-wheel and the apron for imparting a rearward movement to the apron, a clutch forming a part of 125
3. The combination of a main body, ground-wheels carrying said body, a traveling apron forming the bottom of said body, an intermediate mechanism between a ground-wheel and the apron for imparting a forward movement to the apron, a clutch forming a part of 130

such mechanism, means for manually actuating said clutch, and a locking member automatically controlled by the operating means of said detachable connection and adapted to 5 lock the mechanism for effecting a forward movement of the apron in a dormant condition during a rearward movement of said apron, substantially as set forth.

2. In a manure-spreader, the combination 10 of a main body, ground-wheels carrying said body, a traveling apron forming the bottom of said body, an intermediate mechanism between a ground-wheel and the apron for imparting a rearward movement to the apron, 15 a detachable connection forming a part of such mechanism, means for manually actuating said detachable connection, an intermediate mechanism between a ground-wheel and the apron for imparting a forward movement 20 to the apron, a clutch forming a part of such mechanism, means for manually actuating said clutch, and a locking member moving with the actuating means of the detachable connection aforesaid and adapted to be 25 engaged by the aforesaid clutch-actuating means to lock the mechanism for effecting a rearward movement of the apron in a dormant condition during a forward movement of the apron, substantially as set forth.
3. In a manure-spreader, the combination 30 of a main body, ground-wheels carrying said body, a traveling apron forming the bottom of said body, an intermediate mechanism between a ground-wheel and the apron for imparting a rearward movement to the apron, 35 a detachable connection forming a part of such mechanism, means for manually actuating said detachable connection, an intermediate mechanism between a ground-wheel 40 and the apron for imparting a forward movement to the apron, a clutch forming a part of such mechanism, means for manually actuating said clutch, and a locking member controlled by the actuating means of the afore- 45 said detachable connection and adapted to lock the mechanism for effecting a forward movement of the apron in a dormant condition during a rearward movement of said apron, and to be engaged by the clutch-actuating 50 means so as to automatically lock the mechanism for effecting a rearward motion of the apron in a dormant condition during a forward movement of said apron, substantially as set forth.

4. In a manure-spreader, the combination 55 of a main body, ground-wheels carrying said body, a traveling apron forming the bottom of said body, an intermediate mechanism between a ground-wheel and the apron for imparting a rearward movement to the apron, 60 a detachable connection forming a part of such mechanism, means for manually actuating said detachable connection, an intermediate mechanism between a ground-wheel 65 and the apron for imparting a forward move-

ment to the apron, a clutch forming a part of such mechanism, means for manually actuating said clutch, a rock-shaft forming a part of the actuating means of the detachable connection aforesaid, and a pivoted arm operatively connected to said rock-shaft and adapted to lock the mechanism for effecting a forward movement of the apron in a dormant condition during a rearward movement of said apron, substantially as set forth. 75

5. In a manure-spreader, the combination 80 of a main body, ground-wheels carrying said body, a traveling apron forming the bottom of said body, an intermediate mechanism between a ground-wheel and the apron for imparting a rearward movement to the apron, 85 a detachable connection forming a part of such mechanism, means for manually actuating said detachable connection, an intermediate mechanism between a ground-wheel and the apron for imparting a forward movement to the apron, a clutch forming a part of such mechanism, means for manually actuating said clutch, a rock-shaft forming a part 90 of the actuating means of the detachable connection aforesaid, and a pivoted arm operatively connected to said rock-shaft and adapted to be engaged by the clutch-actuating means so as to automatically lock the mechanism for effecting a rearward movement 95 of the apron in a dormant condition during a forward movement of said apron, substantially as set forth.

6. In a manure-spreader, the combination 100 of a main body, ground-wheels carrying said body, a traveling apron forming the bottom of said body, an intermediate mechanism between a ground-wheel and the apron for imparting a rearward movement to the apron, 105 a detachable connection forming a part of such mechanism, means for manually actuating said detachable connection, an intermediate mechanism between a ground-wheel and the apron for imparting a forward movement to the apron, a clutch forming a part 110 of such mechanism, means for manually actuating said clutch, a rock-shaft forming a part of the actuating means of the detachable connection aforesaid, and a pivoted arm operatively connected to said rock-shaft and adapted to be engaged by the clutch-actuating 115 means, so as to automatically lock the mechanism for effecting a rearward movement of the apron in a dormant condition during a forward movement of said apron, and to 120 lock the mechanism for effecting a forward movement of the apron in a dormant condition during a rearward movement of said apron, substantially as set forth.

7. In a manure-spreader, the combination 125 of a main body, ground-wheels carrying said body, a traveling apron forming the bottom of said body, an intermediate mechanism between a ground-wheel and the apron for imparting a rearward movement to the apron, 130

a detachable connection forming a part of said mechanism, means for manually actuating said detachable connection, an intermediate mechanism between a ground-wheel 5 and the apron for imparting a forward movement to the apron, a clutch forming a part of such mechanism, means for manually actuating said clutch, a rotary beater at the end of the main body, an intermediate mechanism 10 between a ground-wheel and the beater for imparting rotation to said beater, a clutch forming a part of such beater mechanism, means for actuating said clutch, an operating connection common to the actuating means 15 of the aforesaid detachable connection and to the means for actuating the clutch of the beater mechanism, and a locking member operatively connected to said operative connection and adapted to lock the mechanism 20 for effecting a forward movement of the apron in a dormant condition during a rearward movement of said apron, substantially as set forth.

8. In a manure-spreader, the combination 25 of a main body, ground-wheels carrying said body, a traveling apron forming the bottom of said body, an intermediate mechanism between a ground-wheel and the apron for imparting a rearward movement to the apron, 30 a detachable connection forming a part of said mechanism, means for manually actuating said detachable connection, an intermediate mechanism between a ground-wheel and the apron for imparting a forward movement 35 to the apron, a clutch forming a part of such mechanism, means for manually actuating said clutch, a rotary beater at the end of the main body, an intermediate mechanism between a ground-wheel and the beater for 40 imparting rotation to said beater, a clutch forming a part of such beater mechanism, means for actuating said beater-clutch, an operating connection common to the actuating means 45 of the aforesaid detachable connection and to the means for actuating the clutch of the beater mechanism, and a locking member operatively connected to said operative connection and adapted to be controlled by the clutch-actuating means to automatically lock the mechanism 50 for effecting a rearward movement of the apron in a dormant condition during a forward movement of the apron, substantially as set forth.

9. In a manure-spreader, the combination 55 of a main body, ground-wheels carrying said body, a traveling apron forming the bottom of said body, an intermediate mechanism between a ground-wheel and the apron for imparting a rearward movement to the apron, 60 a detachable connection forming a part of said mechanism, means for manually actuating said detachable connection, an intermediate mechanism between a ground-wheel and the apron for imparting a forward movement 65 to the apron, a clutch forming a part of

such mechanism, means for manually actuating said clutch, a rotary beater at the end of the main body, an intermediate mechanism between a ground-wheel and the beater for imparting rotation to said beater, a clutch 70 forming a part of such beater mechanism, means for actuating said beater-clutch, an operating connection common to the actuating means of the aforesaid detachable connection and to the means for actuating the clutch of the beater mechanism, and a locking member operatively connected to said operative connection and controlled by said operative connection and by the clutch-actuating means of the apron mechanism and adapted 75 to lock the mechanism for effecting a forward movement of the apron in a dormant condition during a rearward movement of said apron, and to be engaged by the clutch-actuating means of the apron mechanism so 80 as to automatically lock the mechanism for effecting a rearward movement of the apron in a dormant condition during a forward movement of said apron, substantially as set forth.

10. In a manure-spreader, the combination 90 of a main body, ground-wheels carrying said body, a traveling apron forming the bottom of said body, an intermediate mechanism between a ground-wheel and the apron for imparting a rearward movement to the apron, a detachable connection forming a part of said mechanism, means for manually actuating said detachable connection, an intermediate mechanism between a ground-wheel and the 95 apron for imparting a forward movement to the apron, a clutch forming a part of such mechanism, means for manually actuating said clutch, a rotary beater at the end of the main body, an intermediate mechanism between a ground-wheel and the beater for 100 imparting rotation to said beater, a clutch forming a part of such beater mechanism, means for actuating said beater-clutch, a rock-shaft common to the actuating means of the aforesaid 105 detachable connection and to the means for actuating the clutch of the beater mechanism, and a pivoted arm operatively connected to said rock-shaft and adapted to lock the mechanism for effecting a forward movement 110 of the apron in a dormant condition during the rearward movement of said apron, substantially as set forth.

11. In a manure-spreader, the combination 115 of a main body, ground-wheels carrying said body, a traveling apron forming the bottom of said body, an intermediate mechanism between a ground-wheel and the apron for imparting a rearward movement to the apron, a detachable connection forming a part of 120 said mechanism, means for manually actuating said detachable connection, an intermediate mechanism between a ground-wheel and the apron for imparting a forward movement to the apron, a clutch forming a part of 125 said mechanism, means for manually actuating said detachable connection, an intermediate mechanism between a ground-wheel and the apron for imparting a forward movement to the apron, a clutch forming a 130

- part of such mechanism, means for manually actuating said clutch, a rotary beater at the end of the main body, an intermediate mechanism between a ground-wheel and the beater for imparting rotation to said beater, a clutch forming a part of such beater mechanism, means for actuating said beater-clutch, a rock-shaft common to the actuating means of the aforesaid detachable connection and to the means for actuating the clutch of the beater mechanism, and a pivoted arm operatively connected to said rock-shaft and adapted to be controlled by the clutch-actuating means of the apron mechanism so as to automatically lock the mechanism for effecting a rearward movement of the apron in a dormant condition during a forward movement of the apron, substantially as set forth.
12. In a manure-spreader, the combination of a main body, ground-wheels carrying said body, a traveling apron forming the bottom of said body, an intermediate mechanism between a ground-wheel and the apron for imparting a rearward movement to the apron, a detachable connection forming a part of said mechanism, means for manually actuating said detachable connection, an intermediate mechanism between a ground-wheel and the apron for imparting a forward movement to the apron, a clutch forming a part of such mechanism, means for manually actuating said clutch, a rotary beater at the end of the main body, an intermediate mechanism between a ground-wheel and the beater for imparting rotation to said beater, a clutch forming a part of such beater mechanism, means for actuating said clutch, a rock-shaft common to the actuating means of the aforesaid detachable connection and to the means for actuating the clutch of the beater mechanism, and a pivoted arm operatively connected to said rock-shaft and controlled by said rock-shaft and by the clutch-actuating means of the apron mechanism, and adapted to lock the mechanism for effecting a forward movement of the apron in a dormant condition during a rearward movement of the apron, and to be engaged by the clutch-actuating means of the apron mechanism so as to automatically lock the mechanism for effecting a rearward movement of the apron in a dormant condition during a forward movement of said apron, substantially as set forth.
13. In a manure-spreader, the combination of a main body, ground-wheels carrying said body, a traveling apron forming the bottom of said body, an intermediate mechanism between a ground-wheel and the apron for imparting a forward motion to said apron, the same comprising a gear-wheel receiving motion from a ground-wheel, a supporting-arbor for said gear-wheel, a pinion receiving motion from said gear-wheel, a supporting-arbor for said pinion, a chain-wheel mounted on said arbor, the opposed faces of the pinion and chain-wheel having complementary

and chain-wheel having complementary clutch members, a bell-crank lever pivoted to the main body and adapted to impart lateral movement to said chain-wheel, an operating-lever at the front of the main body, lever and link connections between the operating and bell-crank levers, a driving-wheel for the traveling apron, and an operative connection between said driving-wheel and the aforesaid chain-wheel, substantially as set forth.

14. In a manure-spreader, the combination of a main body, ground-wheels carrying said body, a traveling apron forming the bottom of said body, an intermediate mechanism between a ground-wheel and the apron for imparting a forward motion to said apron, the same comprising a gear-wheel receiving motion from a ground-wheel, a supporting-arbor for said gear-wheel, a pinion receiving motion from said gear-wheel, a supporting-arbor for said pinion, a chain-wheel mounted on said arbor, the opposed faces of the pinion and chain-wheel having complementary clutch members, a bell-crank lever pivoted to the main body and adapted to impart lateral movement to said chain-wheel, an operating-lever at the front of the main body, lever and link connections between the operating and bell-crank levers, a driving-wheel for the traveling apron, an operative connection between said driving-wheel and the aforesaid chain-wheel, a spring tending to move the operating-lever in one direction, a catch-piece for holding said lever against the stress of said spring, and means for automatically disengaging said lever from said catch, substantially as set forth.

15. In a manure-spreader, the combination of a main body, ground-wheels carrying said body, a traveling apron forming the bottom of said body, an intermediate mechanism between a ground-wheel and the apron for imparting a forward motion to said apron, the same comprising a gear-wheel receiving motion from a ground-wheel, a supporting-arbor for said gear-wheel, a pinion receiving motion from said gear-wheel, a supporting-arbor for said pinion, a chain-wheel mounted on said arbor, the opposed faces of the pinion and chain-wheel having complementary clutch members, a bell-crank lever pivoted to the main body and adapted to impart lateral movement to said chain-wheel, an operating-lever at the front of the main body, lever and link connections between the operating and bell-crank levers, a driving-wheel for the traveling apron, an operative connection between said driving-wheel and the aforesaid chain-wheel, a spring tending to move the operating-lever in one direction, a catch-piece for holding said lever against the stress of the spring, a pendent arm pivoted on the main body in the path of the forward end of the apron and adapted at the limit of the forward motion of the apron to automatically

disengage said lever from said catch, substantially as set forth.

16. In a manure-spreader, the combination of a main body, ground-wheels carrying said body, a traveling apron forming the bottom of said body, an intermediate mechanism between a ground-wheel and the apron for imparting a forward motion to said apron, the same comprising a gear-wheel receiving motion from a ground-wheel, a supporting-arbor for said gear-wheel, a pinion receiving motion from said gear-wheel, a supporting-arbor for said pinion, a chain-wheel mounted on said arbor, the opposed faces of the pinion and chain-wheel having complementary clutch members, a bell-crank lever pivoted to the main body and adapted to impart lateral movement to said chain-wheel, an operating-lever at the front of the main body, lever and link connections between the operating and bell-crank levers, a driving-wheel for the traveling apron, an operative connection between said driving-wheel and the aforesaid chain-wheel, a spring tending to move the operating-lever in one direction, a catch-piece for holding said lever against the stress of the spring, a pendent arm pivoted on the main body in the path of the forward end of the apron and having an intermediate angular projection adapted at the limit of the forward motion of the apron to automatically disengage said lever from said catch, substantially as set forth.

17. In a manure-spreader, the combination of a main body, ground-wheels carrying said body, a traveling apron forming the bottom of said body, an intermediate mechanism between a ground-wheel and the apron for imparting a rearward motion to said apron, the same comprising a gear-wheel receiving motion from a ground-wheel, a series of annular gears on one face of said gear-wheel, a supporting-arbor for said gear-wheel, an adjustable pinion adapted for engagement with either of said annular gears, a shaft carrying said pinion, means for adjusting said pinion on said shaft, a bearing-sleeve for said shaft mounted in a slideable manner on the arbor aforesaid and provided with a spiral rib and a complementary spiral recess, an operating-arm journaled on said arbor and provided with an inclined projection and a hook-shaped toe adapted for operative engagement with the aforesaid rib, and recess of the bearing-sleeve, a driving-wheel for the traveling apron, and operative connections between said driving-wheel and the pinion-shaft aforesaid, substantially as set forth.

18. In a manure-spreader, the combination of a main body, ground-wheels carrying said body, a traveling apron forming the bottom of said body, intermediate mechanisms between a ground-wheel and the apron for imparting opposite movements to said apron, a rotary beater journaled at the rear of the main body,

an intermediate mechanism between a ground-wheel and the beater for imparting rotation to the beater, a section of chain connecting the ends of the traveling apron together to impart an endless form thereto, a transverse shaft arranged beneath the main body midway its length, a series of supporting-rollers on said shaft, and a vertically-enlarged link arranged at the intersection of the aforesaid chain-section and the tail of the apron and adapted to ride over one of said rollers and lift the tail of the apron above said rollers, substantially as set forth.

19. In a manure-spreader, the combination of a main body, ground-wheels carrying said body, a traveling apron forming the bottom of said body, intermediate mechanisms between a ground-wheel and the apron for imparting opposite movements to said apron, a rotary beater journaled at the rear of the main body, an intermediate mechanism between a ground-wheel and the beater for imparting rotation to the beater, a section of chain connecting the ends of the traveling apron together to impart an endless form thereto, a transverse shaft arranged beneath the main body midway its length, a series of supporting-rollers on said shaft, and a link arranged at the intersection of the chain-section and the tail of the traveling apron and provided with an inclined rib on its underside adapted to ride over one of said rollers and lift the tail of the apron above said rollers, substantially as set forth.

20. In a manure-spreader, the combination of a main body, ground-wheels carrying said body, a traveling apron forming the bottom of said body, intermediate mechanisms between a ground-wheel and the apron for imparting movement to said apron, a rotary beater journaled at the rear of the main body, an intermediate mechanism between a ground-wheel and the beater for imparting rotation to the beater, a pressure-comb formed in sections, means for supporting said sections, and individual yielding connections between said sections and the supporting means, substantially as set forth.

21. In a manure-spreader, the combination of a main body, ground-wheels carrying said body, a traveling apron forming the bottom of said body, intermediate mechanisms between a ground-wheel and the apron for imparting movement to said apron, a rotary beater journaled at the rear of the main body, an intermediate mechanism between a ground-wheel and the beater for imparting rotation to the beater, a pressure-comb formed in sections, a support in common for said sections formed by a transversely-extending shaft, and individual yielding connections between said sections and said shaft, substantially as set forth.

22. In a manure-spreader, the combination of a main body, ground-wheels carrying said

body, a traveling apron forming the bottom of said body, intermediate mechanisms between a ground-wheel and the apron for imparting movement to said apron, a rotary beater journaled at the rear of the main body, an intermediate mechanism between a ground-wheel and the beater for imparting rotation to the beater, a pressure-comb formed in sections, means for supporting said sections and individual yielding connections between said sections and the supporting means consisting of a bolt carried by the supporting means, a pressure-nut on said bolt, and a spring arranged beneath said pressure-nut, substantially as set forth.

23. In a manure-spreader, the combination of a main body, ground-wheels carrying said body, a traveling apron forming the bottom of said body, intermediate mechanisms between a ground-wheel and the apron for im-

parting movement to said apron, a rotary beater journaled at the rear of the main body, an intermediate mechanism between a ground-wheel and the beater for imparting rotation to the beater, a pressure-comb ²⁵ formed in sections, a support in common for said sections formed by a transversely-extending shaft, and individual yielding connections between said sections and said shaft, and each comprising an arm on the shaft, a bolt on said arm, a pressure-nut on said bolt, and a spring arranged beneath said pressure-nut, substantially as set forth.

Signed at Chicago, Illinois, this 30th day of March, 1905.

LEVI H. KELLAM.
